UNITED STATES PATENT OFFICE

132,968

DESIGN FOR AN ELECTRIC FOOD MIXER

Chauncey E. Waltman, Chicago, Ill., assignor to
A. F. Dormeyer Mfg. Co., Chicago, Ill., a corporation of Illinois

Application December 21, 1939, Serial No. 89,064

Term of patent 3½ years

To all whom it may concern:

Be it known that I, Chauncey E. Waltman, a citizen of the United States, residing at Chicago, in the county of Cook and States of Illinois, have invented a new, original, and ornamental Design for Electric Food Mixers, of which the following is a specification, reference being had to the accompanying drawings, forming a part thereof.

Fig. 1 is a side elevational view of an electric food mixer, showing my design;

Fig. 2 is a front elevational view; and

Fig. 3 is a top plan view thereof.

I claim:

The ornamental design for an electric food mixer, as shown.

CHAUNCEY E. WALTMAN.
